UNITED STATES PATENT OFFICE.

EDWARD KAYLOR, OF ALLEGHENY, PENNSYLVANIA.

RAILWAY-CAR TRUCK.

No. 852,387.

Specification of Letters Patent.

Patented April 30, 1907.

Application filed October 17, 1904. Serial No. 228,679.

To all whom it may concern:

Be it known that I, EDWARD KAYLOR, a resident of Allegheny, in the county of Allegheny and State of Pennsylvania, have invented a new and useful Improvement in Railway-Car Trucks; and I do hereby declare the following to be a full, clear, and exact description thereof.

My invention relates to railway car trucks, and has special reference to the side-frames for the same, such as are manufactured or pressed from wrought metal, such as steel.

The object of my invention is to form such a railway car truck side-frame which will be simple and durable in its construction, will be easily and cheaply manufactured and will have a maximum in strength and a minimum in weight.

My invention consists, generally stated, in the novel arrangement, construction and combination of parts, as hereinafter more specifically set forth and described and particularly pointed out in the claims.

To enable others skilled in the art to which my invention appertains to construct and use my improved railway car truck side-frame, I will describe the same more fully, referring to the accompanying drawings in which:

Figure 1 is a side elevation of one of the side-frames and looking at the outside of the same. Fig. 2 is a like view of the frame looking at the inside of the same. Fig. 3 is a top or plan view of the side-frames with the bolster attached thereto in forming the truck. Fig. 4 is a bottom plan view of one of the side frames and showing one-half in section on line 4—4 Fig. 1 through the openings for the journal-boxes. Fig. 5 is an enlarged vertical central section of said side-frame taken on the line 5—5 Fig. 4 through the journal-box openings and looking in the direction of the arrow. Fig. 6 is an inner face view of one end of one of the side-frames showing a modified construction. Fig. 7 is a vertical section of the same on the line 7—7 Fig. 6. Fig. 8 is a side elevation of one of the end-pieces with another form of my invention applied thereto. Fig. 9 is an enlarged section through the same on the line 9—9 Fig. 8, and looking in the direction of the arrow. Fig. 10 is an enlarged section on the line 10—10 Fig. 8 looking in the direction of the arrow. Fig. 11 is a section similar to Fig. 9 and showing a slight modification thereof. Figs. 12 to 17 inclusive illustrate other forms

of my invention. Figs. 18 to 22 represent different views of the construction of the side-frames for six-wheel trucks and Fig. 22 is a cross-section on the line 22—22, Fig. 18. 60

Like symbols of reference herein indicate like parts in each of the figures of the drawings.

As illustrated in the drawings 1 represents my improved railway car truck of the four-wheel type, which is preferably formed of pressed steel and 2 represents the side-frames thereof which have a main member 2' formed from sheet metal and first made to the proper shape or contour to provide for the central portion 3 and the end pieces or portions 4 thereon having the recesses or openings 5' formed therein for the pedestals 5 to hold the journal-boxes (not shown). Projecting inwardly from the top 7 of the main member 2' is the deep flange 8 which is formed thereon by means of suitable dies, which flange can be depressed in the center as shown at 9 or formed in a straight line, if desired as shown at 9' in Fig. 6, while another flange 10 80 is also formed in like manner at the center base 11 of said main member 2', such flange 10 also projecting inwardly and being somewhat less in width than the top flange 8. These flanges 8 and 10 are pressed at right 85 angles from a straight edge at the top 7 and base 11 respectively of the main member 2' and are joined together in forming the truck 1 by a transom or bolster as hereinafter described, while pressed out from the end portions 4 of said main member 2' by means of suitable dies and over each of the openings 5 is the semi-circular portion 12' for forming part of the bearing or spring-cap 12 for the truck-spring (not shown) and the side-edges 95 13' of said openings 5' are flanged inwardly or in the direction of the flanges 8 and 10 to form the guide-bars or plates 13. These guide-bars or plates extend down from the lower edge 12'' of each spring-cap 12 and the inner side-plate 13 connects with a small flange 13' formed on the projecting portion 10' which extends downward from the base 11 of the main member 2', while such flange 10' forms part of and connects with the 100 flange 10 by the upwardly extending flange portion 13''. The outer side plate 13 forms part of and connects with a small flange 8' formed on the base 11' of the projecting end portion 4' and this flange 8' forms part of and connects with a flange 8'' extending around the end face 4'' of said end portion 4 and

forming part of the top flange 8. An end member or piece 14 is attached by rivets 14' to each end-portion 4 of the main member 2' and to form such end piece a plate or sheet of metal is first made to the proper shape or contour and then by means of suitable dies, the semi-circular portion 15' of the other part of the bearing or spring-cap 15 is formed to register with the spring-cap 12 formed on the end portions 4 of the main member 2' for confining said truck spring, while a recess or opening 16 is also formed in each end piece 14 to register with the recesses or openings 5' formed in said end portions 4 in forming the pedestals 5. The side-edges 17' of the opening 16 in said end-piece 14 are flanged outwardly to form the guide-bars or plates 17, such plates 17 extending down from the lower edge 15" of the spring-cap 15 on said end-piece and the inner side plate 17 forms part of and connects with a small flange 18' formed on a projecting portion 18 opposite the projecting portion 10' on the main member 2', while such flange 18' forms part of and connects with an upwardly extending flanged portion 18" forming part of and connecting with a small flange 14" on the base 14" of said end-piece. The outer side plate 17 forms part of and connects with a small flange 19" formed on the base 19' of the projecting end portion 19 opposite the projecting end portion 4' and this flange 19" forms part of and connects with a flange 20" extending around the end-face 20' of said end-piece 14 so as to form part of and connect with the top-flange 20 opposite the top-flange 8 on the end portion 4 of the main member 2'.

The guide-bars or plates 13 and 17 are used to strengthen the parts and support the spring-caps 12 and 15, and they are also used as means for holding and confining the wearing-plates 21 in position, which wearing plates have flanges 21' thereon for fitting over the edges 21" of said plates 13 and 17 to support and secure the same in place. Slots 22' are formed in the wearing plates 21 for the reception of a tie-bar 22 which passes through the same and between raised portions 23 formed on the projecting portions 10' and 18 and projecting end portions 4' and 19 on said main member 2' and end pieces 14 respectively, while such tie-bar 22 is held in place by means of bolts 23' which pass through said projecting portions 10' and 18 and projecting end portions 4' and 19. After the end-pieces 14 are attached to the end-ports 4 on the front face of the main member 2' to form the side-frames 2 of my improved railway car truck 1, the said frames 2 are connected to the transom or bolster 25 extending between the same by means of rivets 25' which pass through the channel-bars 25" of said bolster 25 and through the flanges 8 and 10 on the main member 2' of

the side-frames 2, while such bars 25" are also adapted to carry the plate 27 which is secured thereto and on which is secured the center plate 28 and these plates are provided with a central opening 29 for the reception 70 of a king-bolt 30 for connecting the truck 1 with the body of the car (not shown).

In Figs. 6 and 7 a modification of the construction previously described is shown, in which the end-pieces 14 are attached to the rear or inside face of the end-portion 4 on the main member 2' instead of the outer face, and in this case the end-pieces or portions 4 and 14 are not required to be provided with flanges around the same, except at the outer 80 ends and bottom portions, while the main member 2' has the top and bottom flanges extending around the same. These end-portions or pieces 4 and 14 have the spring-caps, guide-bars and other portions formed 85 in the same manner as that before described and the main member 2' is attached to the transom or bolster through the top and bottom flanges, except that in using the straight top face on the main member the channel-bars 25" are depressed, as at 26.

In Figs. 8, 9 and 10 there is shown another form of my improved railway car truck, in which the separate wearing-plates 21 are dispensed with, and in this case a T-bar 95 31 is bent into U-shape, so as to fit within and between raised portions 31' formed in the end portion 4 of the main member 2' and in the end-piece 14 around the openings 5 and 16 respectively therein. This bar 31 is held in place by means of rivets 32 passing through said raised portions 4 and end-piece 14 and through the web-portion 32' on said bar 31, while said web-portion is cut away, as at 33', so that a tie-bolt 33 can connect each end of 105 said bar 31 and pass through the body 32" of the same.

In Fig. 11 the guide-bars or plates 13 and 17 for the pedestals 5 and shown in the figures just described are dispensed with, and 110 in such case the wearing-plates 21 are placed around the body 32" of the bar 31.

In Figs. 12 and 13 there is illustrated another form of my improved railway car truck, in which the end portion 4 of the main 115 member 2' has an integral end-piece 34 formed at the end thereof, so that by having first formed the spring-caps, guide-bars or plates, etc. thereon and in the same manner as before described, and end-piece 34 can 120 be folded inwardly along the dotted line 35 to register the spring-caps, guide-bars or plates with those on the end portion of the main member and be attached to said main member as before described. In this case 125 the tie-bar can pass through openings 36 formed by recesses 36' in said end-ports 4 and end-piece 36 when these parts register with each other and these parts can also be further secured by riveting through openings 130

37 formed in projections 38 below the recessed portions 36'.

In Figs. 14 and 15 there is illustrated another form of my invention in which the 5 main member 2' is similar to the one described in the preceding paragraph, except that the integral end-piece 34' is adapted to be folded at the base instead of at the end portion 4' on the main member 2' and by such 10 folding a loop 34" will be formed on each pedestal for the reception of the tie-bar.

In Figs. 16 and 17 another form of my invention is illustrated in which the side-frame 2 is formed of two main members 2', 2'', the 15 one analogous to the other, except that they are right and left and the two-members are arranged to overlap or fit within the other as will be seen by reference to Fig. 17 of the drawings, in which a flange 8^a is shown on the member 2'' as fitting over the flange 8 on the member 2', and each member is provided with the spring-caps, guide-bars, tie-bar recesses, etc.

In Figs. 18 to 22 there is illustrated a side-frame for use in a six-wheel truck which contains the invention, and in such case a pedestal portion 5" is formed at each end and in the center of the main member, while the attachable pedestal portions 14 are placed on 25 the outside of said main member and both the portions forming each pedestal 5 have the spring-caps, guide-bars and other portions formed thereon in the manner before described.

35 It will be obvious that a number of pedestals can be placed in the side-frame and any suitable form of a transom or bolster can be attached to said side-frame and in any suitable manner, while a flange may be formed 40 on the inner edge of the attachable or connecting portions if desired in some cases, and in other cases all of the flanges shown on said portions may be dispensed with if desired. These and various other modifications and 45 changes in the design and construction of my improved car truck may be made without departing from the spirit of my invention, or sacrificing any of its advantages.

It will thus be seen that my improved railway car truck will be provided with a side frame of great strength and simplicity, which 50 will be capable of being strengthened at the center or any portion as may be found necessary in practice under different requirements 55 and without adding any unnecessary weight to the balance of the frame.

It will also be seen that such a side-frame 60 will overcome many defective trucks now in use or manufactured caused by the distortion of the metal in the bending, pressing or other manner of forming the frame, as well as owing to the complicated and difficult bends necessary in these constructions of trucks, and if the thickness of metal is increased additional dead weight is added to the truck, so

that by my invention a certain thickness can be successfully operated upon at all times.

It will further be seen that the weakness usually incident in the outer member of the yoke or pedestal embracing the journal-boxes 70 will be overcome by the use of a double thickness of metal at this point of any desired gage which will be flanged and formed to give the greater strength to such pedestals and resist any pressure brought against the same by the 75 brakes, while if desired the central portion of the side-frame may be formed of comparatively light thickness of metal on account of there being a surplusage of carrying strength at this point.

80 It will also be obvious that the construction of the parts forming these pedestal portions of the side-frame gives great strength to the pedestals and rigidity to the construction between said pedestal portions and the bolster or transom, while the single thickness of metal at the center of the frame will give sufficient resiliency to said frame and allow it to conform to the curves of the track on which the truck is used.

90 What I claim as my invention and desire to secure by Letters Patent is:

1. A sheet metal side-frame for a railway truck comprising a flanged main-member having an integral pedestal portion formed 95 thereon, and another pedestal portion adapted to be attached to said integral portion to form doubled sheets of metal.

2. A sheet metal side-frame for a railway truck comprising a flanged main-member 100 having an integral pedestal portion formed thereon, another pedestal portion adapted to be attached to said integral portion to form doubled sheets of metal, and an integral flanged portion on said pedestal portions to 105 form a spring-cap.

3. A sheet metal side-frame for a railway truck comprising a flanged main-member having an integral pedestal portion formed 110 thereon, another pedestal portion adapted to be attached to said integral pedestal portion to form doubled sheets of metal, and an integral flanged portion on said pedestal portions to form guide-bar plates.

4. A sheet metal side-frame for a railway 115 truck comprising a flanged main-member having an integral pedestal portion formed thereon, another pedestal portion adapted to be attached to said integral portion to form doubled sheets of metal, and integral flanged 120 portions on said pedestal portions to form a spring-cap and guide-bar plates.

5. A sheet metal side-frame for a railway truck comprising a flanged main-member having an integral pedestal portion formed 125 thereon, and another pedestal portion adapted to be attached to said integral portion to form doubled sheets of metal, said pedestal portions having recesses therein for the reception of a tie-bolt or bar.

6. A sheet metal side-frame for a railway truck comprising a flanged main-member having an integral pedestal portion formed thereon, another pedestal portion adapted to be attached to said integral portion to form doubled sheets of metal, and raised portions on said pedestal portions for the reception of a tie-bolt or bar.
7. A sheet metal side-frame for a railway truck comprising a flanged main-member having an integral pedestal portion formed thereon, another pedestal portion adapted to be attached to said integral portion to form doubled sheets of metal, raised portions on said pedestal portions for forming recesses between said portions, and a tie-bolt or bar secured to and fitting within said recesses and between said pedestal portions.
8. A sheet metal side-frame for a railway truck comprising a flanged main-member, pedestal portions on said main-member for forming a pedestal, a yoke formed of a T-bar for being secured to and fitting around and between said pedestal portions to form wearing surfaces by its body portion, said yoke having its flanged portion cut-away at its base to receive a tie-bolt or bar.
9. A sheet metal side-frame for a railway truck comprising a flanged main-member, pedestal portions on said main-member for forming a pedestal, a yoke secured to and fitting around and between said pedestal portions and wearing-plates fitting over and around said yoke.
- 35 10. A sheet metal side-frame for a railway

truck comprising a flanged main-member, pedestal portions on said main-member for forming a pedestal, a yoke formed of a T-bar for being secured to and fitting around and between said pedestal portions, and wearing-plates fitting over and around the body portion of said yoke.

11. A sheet metal side-frame for a railway truck comprising a flanged main-member, pedestal portions on said main-member for forming a pedestal, a yoke formed of a T-bar for being secured to and fitting around and between said pedestal portions, said yoke having its flanged portion cut-away at its base to receive a tie-bolt or bar, and wearing-plates fitting over and around the body portion of said yoke.

12. A sheet metal side-frame for a railway truck comprising a flanged main-member, pedestal portions on said main-member for forming a pedestal, a yoke formed of a T-bar for being secured to and fitting around and between said pedestal portions, said yoke being cut-away at its base and having openings through its body portion at such cut-away portion, a tie-bolt or bar passing through and secured within said openings, and wearing-plates fitting over and around the body-portion of said yoke.

In testimony whereof, I the said EDWARD 65 KAYLOR have hereunto set my hand.

EDWARD KAYLOR.
